Primary Examiner — Melanie H Tung*Assistant Examiner* — Darmawan Truong(74) *Attorney, Agent, or Firm* — Hayes Soloway P.C.(57) **CLAIM**

We claim the ornamental design for wearable device display screen with graphical user interface, as shown and described.

DESCRIPTION

FIG. 1 is a front view of a first image in a sequence for a wearable device display screen with graphical user interface; FIG. 2 is a front view of a second image thereof; FIG. 3 is a front view of a third image thereof; FIG. 4 is a front view of a fourth image thereof; FIG. 5 is a front view of a fifth image thereof; and, FIG. 6 is a front view of a sixth image thereof.

The broken lines showing the wearable device display screen form no part of the claimed design. The remaining broken line showing text, numbers, and portions of the graphical user interface form no part of the claimed design. The appearance of the image transitions sequentially between the images shown in FIGS. 1-6. The process or period in which an image transitions to another image forms no part of the claimed design.
